UNITED STATES PATENT OFFICE.

ROBERT D. STEWART, OF CLEVELAND, NORTH DAKOTA; THE FIRST NATIONAL BANK OF ARLINGTON, SOUTH DAKOTA, ADMINISTRATOR OF SAID ROBERT D. STEWART, DECEASED.

GATE LOCK.

Application filed October 20, 1926. Serial No. 142,923.

The present invention is directed to improvements in gate locks.

The primary object of the invention is to provide a lock more particularly designed for use in connection with wire strand or frameless gates, the construction being such that the gate can be easily opened or closed, the lock being of such construction as to exert tension upon the gate, to hold the same securely in its closed position.

Another object of the invention is to provide a device of the character so constructed that when in its locked position the passage of small animals through the gate opening is prevented, the construction being such, however, that the gate can be held partially open to permit passage of small animals or persons when desired.

In the accompanying drawing:

20 Figure 1 is an elevational view showing the gate in its locked position.

Figure 2 is a similar view, showing the gate partially unlocked.

25 Figure 3 is a top plan view of Figure 2.

Figure 4 is a top plan view of Figure 1.

Figure 5 is a sectional view on line 5—5 of Figure 2.

30 Figure 6 is a sectional view on line 6—6 of Figure 2.

Referring to the drawing, 1 and 2 designate the gate posts, and 3 the gate which is formed from a plurality of strands of horizontally disposed cables 4, having one of their ends suitably secured to the post 1.

35 The lock beam 5 is formed from a pair of sections 6 and 7, the section 6 having a longitudinal groove 8 formed upon its inner face and when the sections are secured together by the bolts 9 the groove is closed by the associated sections, and constitutes a bearing, the purpose of which will later appear. The cables 4 are secured to the lock beam 5 in order that when the gate is closed the cables will be stretched across the gate opening.

45 Associated with the lock beam 5 is a crank shaft 10, the intermediate portion of which is journaled in the bearing provided by the groove 6. The lower end of the crank shaft is journaled in a bearing 11 formed in the plate 12 which is embedded in the ground adjacent the gate post 2 and anchored thereto by a chain 12'. The upper end of the crank shaft is provided with a terminal eye

13, which terminates in a substantially horizontally disposed operating lever 14.

The section 7 of the lock beam is somewhat longer than its companion section, in order that the extended end thereof will constitute a stop 15 for the lever 14 when the gate is closed.

A band 16 is secured to the post 2 in any suitable manner and substantially in the same plane as the eye 13, said band having an eye 17 to which is secured one end of the chain 17', the other end of which has a hook 18 connected thereto. This hook is capable, when engaged with the eye 13, to hold the gate securely closed or in a partially open position.

70 When the hook 18 is fully engaged from the eye 13 the beam 5 can be lifted from the plate 12 and carried to one side of the roadway, thus leaving the gate opening unobstructed to permit the passage of vehicles 75 and stock.

To securely close the gate the hook 18 is engaged in the eye 13 and as the lever 14 is swung towards the post 2 the crank shaft 10 will move past center and exert a tension upon the cables 4 forming the gate. This lever can continue to swing until the upper end thereof engages the stop 15 and the lever engages the post 2, and at which time the cables are taut.

85 To open the gate it is only necessary to reverse this operation. Should it be desired to only partly open the gate in order to provide a small passage between the beam 5 and post 2, the lever is swung away from the post, and the fact that the hook is not disengaged from the eye the beam will be sustained in a vertical position, as shown in Figure 1 of the drawing. In this manner a small space is provided to permit 90 a person to pass through the gate opening without fully opening the gate. By connecting the hook 18 and plate 12 to the post 2 by the respective chains 17' and 12', permit said hook and plate to be adjusted 95 relative to post 2 in order to take up slack in the cables 4 of the gate should they stretch. This is accomplished by simply changing the link connections between the posts and the chains 17' and 12'.

100 Having thus described the invention, I claim:

1. The combination with a gate, of a post,

a lock beam carried by the gate and having a stop thereon, a crank shaft journaled longitudinally in the beam and having its lower end journaled in the roadway, the upper end of said crank shaft having an operating lever and an eye, a hook carried by the post for detachably engaging the eye, said lever being operable to swing the upper end of the crank arm into engagement with the stop and held engaged therewith by the tension of the gate.

2. The combination with a gate and a post, of a hook flexibly and adjustably connected with the post, a lock beam carried by the gate, said beam having a crank shaft operatively connected therewith, means for detachably securing the hook to the crank shaft, said crank shaft having an operating

lever capable, when swung in one direction to exert tension simultaneously upon the hook and its connection and gate and to relieve the tension when swung in a reverse direction.

3. The combination with a gate and post, of a locking beam consisting of a pair of sections, a crank shaft journaled in the beam and between the sections thereof, the crank shaft having an eye terminating in an operating lever, a detachable connection between the post and eye, said lever, when swung in one direction exerting tension upon the gate and connection, as and for the purpose set forth.

In testimony whereof I affix my signature.

ROBERT D. STEWART.
